UNITED STATES PATENT OFFICE.

STINA K. WILSON, OF RICHMOND HILL, NEW YORK.

INTERNAL-BATH APPARATUS.

Application filed December 9, 1922. Serial No. 605,780.

To all whom it may concern:

Be it known that I, STINA K. WILSON, a citizen of the United States, residing at Richmond Hill, in the county of Queens, city and State of New York, have invented an Improvement in Internal-Bath Apparatus, of which the following is a specification.

It is not generally recognized, but nevertheless it is a fact, that a large percentage, at least, of the various ills of humanity are attributable to irregular habits resulting in a more or less congested and uncleanly condition of the colon and lower intestines. It is also recognized in many cases, at least, that physics or purgatives are not sufficient to overcome this condition, and on the other hand oftentimes rather aggravate the same. It is furthermore recognized that the internal bath in the form of the more or less commonly known enema is undoubtedly advantageous, but is not sufficient in many cases, particularly when chronic, to relieve or overcome the source of many troubles. The object of my invention is the provision of an apparatus by which, either with the assistance of a nurse or by himself, the patient may readily cleanse the colon and lower intestines of the mucous and other poisonous slimy matters which inevitably accumulate there, and in order to obtain the best results these injurious matters should be removed by being washed away after all or substantially all the waste or solid matter is removed by a suitable physic or enema.

My invention preferably comprises a tank or receptacle in which the water or other liquid employed may be suitably supplied and maintained at a given temperature, together with apparatus by which the liquid may be conveyed from the tank and caused to flow, preferably continuously, to and from the colon and lower intestines of the patient, suitable means being also provided for the patient to rest upon and for the disposal of the waste matter as the same flows from the body. Furthermore the apparatus may be constructed in such a manner as to be placed in hospitals and homes as an addition to the present equipment, or may be so constructed as to form a part of entirely new installations.

The apparatus made in accordance with my invention will be hereinafter more par-

ticularly described in connection with the accompanying drawings, in which,—

Fig. 1 is an elevation of the internal bath apparatus made in accordance with one form of the invention.

Fig. 2 is a section of the patient's support or board taken on the line 2—2, Fig. 1.

Fig. 3 is a front elevation of a form of apparatus comprising my invention adapted for installation in new buildings, such as hospitals, residences and the like.

Fig. 4 is a partial section illustrating the manner in which the tank as shown in Fig. 3 is mounted and

Fig. 5 is a sectional elevation showing the manner in which the board or patient's support may be disposed of when not in use.

Referring to the drawing, and particularly to Figs. 1 and 2, it will be seen that in carrying out the invention I employ a tank 10. This may be made of any suitable configuration and of any desirable material and preferably is provided with a cover 11. The tank may be supported in any desired manner so as to be placed at the necessary elevation to obtain sufficient pressure for the purposes intended in the use of the liquid as the same is supplied from the tank. The tank may be filled by supply pipes 12 and 13, the one for hot water or other liquid, and the other for cold water or other liquid.

In a suitable position in the pipe 12 there is a valve 14, and similarly in a suitable position in the pipe 13 there is a valve 15. These valves, as will be understood, are employed to control the flow of the water or other liquid through the pipes and the pipes are connected to any suitable sources of supply. It therefore follows that by the manipulation of the valves the tank may be filled and maintained with the necessary quantity of liquid therein at substantially any required temperature. In order, however, to ensure that the temperature of the liquid in the tank will be uniform I may fit the cover with a small motor indicated at 16 with the shaft 17 thereof passing through the cover and provided at its extremity with a fan-like or propeller structure or agitator 18 in order to cause a circulation of the water to effect a uniform temperature thereof. In a suitable position, preferably at the bottom of the tank, the same is provided with an outlet 19, and connected in a pipe

20 leading therefrom is a valve 21 by which the flow of the liquid from the tank may be controlled.

5 Detachably connected to the end of the pipe 20 I employ a rectal tube of rubber or any other suitable material. 23 also indicates a rectal tube, which, as illustrated, is attached to the rectal tube 22 at 24, although, as will be understood, the tubes 10 may be made separately, or the tube 23 may be adjustably connected to the tube 22. The outlet orifice at the end of the tube 22 is indicated at 25. The inlet orifice to the tube 23 is indicated at 26, and the outlet orifice 15 of the tube 23 is indicated at 27.

The apparatus also includes a patient's support which may be in the form of a board or couch 28. This couch is preferably supported on legs 29 and its surface is 20 inclined longitudinally and slightly curved transversely so as to prevent any of the waste liquid from flowing otherwise than to the outlet or drain 30 from which, by a suitable pipe connection 31 or otherwise, this 25 waste may be conveyed to a receptacle 32. In this structure the patient's support and the receptacle are independent of each other and separately adapted to be placed in the necessary position for use. The apparatus 30 also includes a pipe 24' passing through the bottom of the tank and into the same to a predetermined extent to form an overflow for the tank and through which, as will be apparent, any excess of the liquid in the 35 tank may pass to the drain at the lower end of the patient's support.

In the use of the apparatus, the patient 40 preferably lies on the couch or support on the right side and the rectal tube 22 is passed into the rectum and into and through the colon and lower intestines to the desired extent, depending, of course, upon the height to which it is desired to flush or cleanse the parts. The inlet end of the rectal tube 23 45 is preferably adjusted so as to remain approximately at the rectum so that the water or other liquid suitably prepared for the purposes intended may pass through the rectal tube 22 and after having flushed the intestines and colon may pass with the mucous and slimy and gaseous matters through the rectal tube 23 to the outlet or discharge from the support to the waste tank or receptacle 32. This form of the apparatus is 55 adapted for use in places that are already established, and as will be apparent may be readily installed at comparatively small expense.

50 Referring to the form of the invention shown in Figs. 3, 4 and 5, which is more especially adapted for new installations, it will be seen that I employ a slab 33 or similar structure which is adapted to be set in a wall. Like the apparatus hereinbefore 55 described this includes a tank 34 made in

any desired shape and of any suitable substance and preferably mounted upon supporting guideways or tracks 35 by means of brackets 36 secured to or made integral with the rear wall of the tank so that the 70 tank may be adjusted to various heights and secured in any desired position within the limits of its adjustment by means of set screws 37 or otherwise in order to vary the head of the liquid supplied in the flushing 75 apparatus and thus regulate the pressure of the same. In this form of the invention there are supply pipes 38 and 39 for the hot and cold liquid supply and fitted respectively with valves 40 and 41 by means of 80 which the flow of the liquid supplied to the tank may be controlled. In this form of the invention, however, the tank is preferably fitted with a partition wall 42 dividing the same into compartments 43 and 44, the compartment 43 being the supply compartment into which the supply pipes empty, and the compartment 44 being that from which the liquid is conveyed for the flushing 85 purposes. It will be apparent that with this construction the water being carried to the bottom of the compartment 43 is initially mixed therein and is caused to flow over the upper edge of the partition wall 42 before passing into the compartment 44 where it 90 may be additionally mixed by means of a motor 45 mounted on the cover 46 of the tank and the motor shaft 47 which turns the fan or propeller like agitator placed adjacent the bottom of the compartment 44 in 95 order to ensure an even temperature in the supply liquid before the same leaves the tank. In this construction the outlet from the tank is indicated at 49. To this is connected a pipe 50 in which there is a valve 51 100 for regulating the flow of the liquid from the tank. The overflow pipe from the tank in this form of the invention is indicated at 52. As in the other form of the invention a flexible rectal tube 53 is attached at one end to the discharge end of the supply pipe 50 and a discharge rectal tube 54 is associated in the same or an equivalent manner with the rectal tube 53.

105 In this structure the couch or board for supporting the patient is indicated at 55 and is preferably inclined longitudinally as well as provided with a slightly concave surface transversely in order to provide for proper drainage to carry away the refuse in 110 the flushing operation. As illustrated the patient's support 55 may be suitably hinged, as indicated at 56, to a carriage 57 adapted to move into and out of a compartment 58 provided for this purpose in the wall in 115 which the slab 33 is mounted, the slab being provided with an opening 59 to permit the patient's support to pass through the same. Hinged to the underside of the patient's support there are legs 60 which, as illustrated, 120

- also may be folded against the bottom of the support when the same is not in use. Also as illustrated, the opening in the slab 59 may be provided with a cover 61 in order to close the opening and completely conceal the support board when the same is not in use. In this instance, as in the other form of the invention, the support board is provided at the lower end with a discharge opening 62 to which may be connected a flexible or other pipe 63 adapted to be connected to an outlet connection 64 leading to the sewer or other convenient place of discharge. Also as illustrated, in this, as well as in the other form of the invention, the tank may be provided with a thermometer 65 in order for the operator to determine the temperature of the liquid being used. The use of this form of the invention is precisely similar to that hereinbefore described in connection with the apparatus shown in Figs. 1 and 2 of the drawing.
- I claim as my invention:
1. An internal bath apparatus comprising a slab, a tank, means for adjusting the tank to position relatively to the slab, means for supplying a liquid to the tank and controlling the temperature thereof, a patient's support and drain board associated with the slab, and devices leading from the tank for continuously conveying liquid from the tank and causing the same to pass to and from the colon and intestines of a patient to flush the same.
  2. An internal bath apparatus comprising a slab, a tank, means for adjusting the tank to position on the slab, means for constantly supplying a liquid to the tank and regulating the temperature thereof, a patient's support and drain board, means for hingedly connecting the patient's support and drain board to the said slab, and devices for continuously conveying the liquid from the tank and causing the same to pass to and from the colon and intestines of a patient to flush the same.

3. An internal bath apparatus comprising a slab, a tank, means for adjusting the tank to position on the slab, means for constantly supplying a liquid to the tank and controlling the temperature thereof, a patient's support and drain board adapted to permit a patient to lie thereon in a reclining position, there being an opening in the said slab providing for communication with a compartment at the rear thereof adapted to receive the said patient's support and drain board, a carriage slidably adjustable in the said compartment, means for hingedly connecting the patient's support and drain board to the carriage, means for supporting the patient's support and drain board in position for use, and devices for conveying the liquid from the tank and permitting the same to flow continuously from the colon and intestines of a patient to flush the same.

Signed by me this 24th day of November, 1922.

STINA K. WILSON.
